UNITED STATES PATENT OFFICE.

WILLIAM H. HEULINGS, JR., OF PHILADELPHIA, PENNSYLVANIA, ASSIGNOR,
TO JOHN A. BRILL, OF PHILADELPHIA, PENNSYLVANIA.

WINDOW FOR CARS.

No. 850,157.

Specification of Letters Patent.

Patented April 16, 1907.

Application filed May 11, 1906. Serial No. 316,267.

To all whom it may concern:

Be it known that I, WILLIAM H. HEULINGS, Jr., a citizen of the United States, and a resident of the city and county of Philadelphia and State of Pennsylvania, have invented a new and useful Improvement in Windows for Cars, of which the following is a specification.

The object of my invention is to provide a device of this kind in which large windows are provided which are closed by at least two sashes and provided with means on one of the sashes whereby the other sash is automatically locked or unlocked to the first sash at appropriate parts of the movement. This object is accomplished by means of my invention, one embodiment of which is hereinafter described.

For a more particular description of my invention reference is to be had to the accompanying drawings, forming a part hereof, in which—

Figure 1 is a section taken through the window of a car provided with my improvement. Fig. 2 is a sectional view taken on the line 2 2 of Fig. 1. Fig. 3 is a similar section taken on the line 3 3 of Fig. 1. Fig. 4 is a plan view of my improved interlocking mechanism. Fig. 5 is a sectional view on the line x x of Fig. 4. Figs. 6 and 7 are sectional views taken on the line x x of Fig. 4, showing the parts in the various positions they occupy during the united movement of the sashes. Fig. 8 is an enlarged perspective view of my improved fastener on a sash. Fig. 9 is a front elevation of the same. Fig. 10 is a plan view of a portion of the catch.

Throughout the various views of the drawings similar reference characters designate similar parts.

The car 1 is provided with the usual post 2, which supports the roof 3 and head-lining 4, and the usual uprights 5 for the deck-roof of the car. The windows are closed by two sashes, a lower, 6, and an upper, 7, which move in suitable slideways 8 in the post 2. Flanges 9 are fixed to each of the side edges of the sash 7 and these flanges 9 are adapted to receive the lower sash 6, as indicated in Fig. 2.

When the sash 6 is raised from the position shown in Fig. 1, it comes in contact with a bell-crank lever or catch 10, which is pivoted on a spindle 11, suitably supported in standards 12, which have a downwardly-projecting flange 13, by means of which the standards

12 are secured by screws 14 to the upper edge of the sash 7. Preferably two of the standards 12 are placed on each sash, one at each side; but as they are identical it is sufficient to show and describe one. The standards 12 have also a laterally-extending projection 15, which extends far enough to have its cross-bar 16 engaged by the lever 10 when raised. The spindle 11 has also an antifriction-roller 17 mounted upon it, and a similar roller 18 is placed on a spindle 19, which is fixed in the lever 10 and runs parallel with the spindle 11.

Below the roller 18 is a downwardly-extending web 20, which is preferably made integral with the lever 10, and this web 20 at its lower end is provided with two laterally-extending projections 21 and 22, respectively. The projection 21 is bifurcated, so as to straddle the guiding-strap 23, which passes up between the rollers 17 and 18 and is secured at 24 and 25 to the walls of the car by any suitable means. This strap 23 preferably follows the outline of the roof in a general way and is so shaped as to properly guide the movement of the upper ends of the sashes, as will appear below. The outer ends of the projection 21 enter a recess 26, which is partially filled by a piece of metal 27, inserted at its upper end, which piece of metal is held in position by a screw 28 or in any other suitable manner, and the metal piece is so proportioned and arranged that the projection 21 rests therein when the sash 7 is in its lowest position and is held in this position by means of a leaf-spring 29, placed under the flange 13, as indicated in Fig. 5.

The projection 22 is inoperative when the projection 21 is in the socket 26 and in engagement with the metal piece 27. However, it becomes operative when the sash 6 is raised, as shown in Fig. 6, so that its upper edge impinges against the lever 10 and raises it until its outer end strikes the cross-bar 16 of the laterally-extending arms 15. When in this position, the projection 21 is withdrawn from the recess 26 and is then against the strap 23, which it straddles. When raised a little more, as shown in Fig. 7, the strap 23 positively holds the projection 21 and prevents any lateral movement. Meanwhile the projection 22 has entered a recess 30, which is preferably reinforced at its edges by a metal socket 31. This socket 31 and the upper edge of the projection 22 are so shaped as to fit each other, as shown in

Figs. 6 and 7—that is, the upper wall of the socket 31 is not cylindrical, but slightly conical and flared toward the web 20, so that the socket-piece 31 and projection 22 will readily disengage at the appropriate time, as described below.

The operation of my improved device is as follows: Assuming the parts to be in the position as indicated in Fig. 5, when the lower sash 6 is raised, as indicated in Fig. 6, so that its upper edges impinge against the lever 10 and raises it into contact with the crossings 16, the projection 21 is withdrawn from engagement with the metal piece 27, and the projection 22 is placed in engagement with the socket-piece 21 against the action of the spring 29. As soon as the sashes are raised together the projection 21 straddles the guiding-strap 23, as above described, so that it is impossible for the projection 22 to be withdrawn from the socket 30 while the projection 21 is in engagement with the strap 23. The antifriction-rollers 17 and 18 permit an easy movement along the guiding-strap 23 until the sashes are raised into the position shown by dotted lines in Fig. 1, where they are held by a bolt (not shown) which rests in a socket 32, which may be of any suitable form. When the sashes are lowered, the bolt 30 is first withdrawn from the socket 32, and the sashes are then brought down together until the upper sash 7 reaches its lowermost position, where it remains. The continued downward movement of the sash 6 forces the projection 22 to leave the socket 31, and this action is accelerated by the spring 29, so that the projection 21 swings into the notch 26 and engages the metal piece 27, whereby the upper sash is locked in its position against upward movement, and the lower sash 6 then continues into the position indicated in Fig. 1.

From the foregoing it is apparent that my improved device positively locks the two sashes together, so that they cannot become separated when in the roof pocket or chamber, so that the tendency to separate in this chamber is obviated and one sash cannot slide or move without regard to the other, and thereby cause the sashes to become jammed when an attempt is made to remove them from this chamber.

It is obvious that my invention may be embodied in various other forms, so that I do not regard it as limited to the structure herein shown and described, but as broad enough to cover all structures that come within the scope of the annexed claims.

Having thus described my invention, what I claim is—

1. In a device of the class described, posts with grooves forming slideways, two sashes moving in said slideways, and means for positively locking one sash to the other when the two are raised into the roof-chamber.

2. In a device of the class described, posts with slideways, an upper and a lower sash moving in said slideways, and means on the upper sash for positively engaging and locking the lower sash when the two are raised into the roof-chamber.

3. In a device of the class described, posts with slideways, upper and lower sashes moving in said slideways, and automatic means for causing said sashes to interlock when raised together in said slideways.

4. In a device of the class described, posts with slideways, a pair of sashes moving in said slideways, a guiding-strap for determining the movement of said sashes, a projection on the upper sash engaging said band, flanges on said upper sash adapted to receive said lower sash, and means on one of said sashes for causing them to interlock when raised.

5. In a device of the class described, posts with slideways therein, a pair of sashes movable in said slideways, a guiding-strap, a projection on one of said sashes for engaging said strap, flanges on one of said sashes adapted to receive and inclose the edges of the other sash, a projection on the flanged sash, at the upper edge thereof, which is adapted to be engaged by the lower sash and interlocking means adapted to lock the sashes together when they are raised.

6. In a device of the class described, posts with slideways, upper and lower sashes movable in said slideways, a guiding-strap for determining the movement of said sashes, flanges on the upper sash adapted to receive the lower sash, a socket-piece in the lower sash, a standard secured to the upper edge of the upper sash, a bell-crank catch pivoted in said standard, an arm adapted to be engaged by the upper edge of the lower sash, and two projections, one adapted to engage said strap, and the other adapted to engage said socket-piece.

7. In a device of the class described, posts with slideways, upper and lower sashes moving therein, a bell-crank catch pivotally mounted on one sash and adapted to be engaged by the other and means for positively holding said catch in engagement with a sash when the sashes are raised together.

8. In a device of the class described, posts with slideways, upper and lower sashes moving therein and a guiding-strap, a bell-crank catch pivotally mounted on the upper sash, two projections on said catch, one adapted to engage said lower sash, and one adapted to engage said guiding-strap.

Signed at Philadelphia, Pennsylvania, this 9th day of May, 1906.
